Primary Examiner — Jack Reickel(74) *Attorney, Agent, or Firm* — Birch, Stewart, Kolasch & Birch, LLP(57) **CLAIM**

The ornamental design for a display screen or portion thereof with graphical user interface, as shown and described.

DESCRIPTION

The FIGURE is a front view of a display screen or portion thereof with graphical user interface showing the claimed design.

The dashed and square-dotted broken line showing of text and graphical user interface elements form no part of the claimed design. The dot-dashed lines show a display screen or portion thereof and form no part of the claimed design.
